UNITED STATES PATENT OFFICE.

EDGAR BEVERLEY FENBY, OF COVENTRY, ENGLAND.

INFOLDING-MACHINE.

1,111,649.

Specification of Letters Patent. Patented Sept. 22, 1914.

Application filed July 13, 1912. Serial No. 709,261.

To all whom it may concern:

Be it known that I, EDGAR BEVERLEY FENBY, subject of the King of Great Britain, residing at Coventry, England, have invented 5 certain new and useful Improvements in Infolding-Machines, of which the following is a specification.

In machines for folding collar, cuff and like blanks, it is frequently desired to alter 10 the sequence in which the edges are folded, thus, it is sometimes desired to fold the sides first, and the ends last, or it may be desired to fold one or other of the sides first then fold the ends and then fold the other side. 15 The purpose of this is to get various forms of lock corners.

According to the present invention the operating members for the side and end folders are all adjustable and the adjusting mechanism 20 is operated from a common member which may be moved into various set positions to adjust one or more of the operating members and leave the others undisturbed. In this way the machine tender has merely 25 to move the adjusting handle to an indicated point in order to obtain any of the four different sequences.

I shall first of all describe the general construction and operation of a folding machine 30 suitable for folding a collar or cuff blank and shall then proceed to deal with the novel features and improvements in the folding mechanism according to the present invention.

Generally speaking these improvements deal with the mechanism for adjusting the folder for different sizes of collars and different sequences of operation.

Referring to the accompanying drawings:—Figure 1, is a side elevation of the machine. Fig. 1^a, is a detail view of the operating lever for the rotatable columns 2. Fig. 2, is a detail view of the operating mechanism for the end folder. Fig. 3, is a front elevation of the machine. Fig. 4, is a plan view showing the arrangement of the adjusting mechanism for altering the sequence of the folding operations. Fig. 5, is a diagrammatic view illustrating the operation 45 of the mechanism shown in Fig. 4. Fig. 5^a, is a view of the folded blank. Fig. 6, is a cross sectional view through the body of the machine. Fig. 7, is a plan view, and Fig. 8, is an elevation of the end folder.

The blank A (Figs. 5^a and 6) to be folded is laid flat on the recessed top of the mov-

able folders c, which are mounted in carriers b and the presser plate d, which is guided and supported in the frame a. The folders c, are shown in Fig. 6, moved into their folding position, this movement being effected by the centrally pivoted levers r, carrying at their lower ends rollers q, which engage with cams 54-54' and 56, 56', to move the folders at the desired times and in the desired sequence as described more fully hereafter.

The present invention is more specifically directed to the means for timing the operation of the folders so that they may be moved in variable sequence.

The flat blank A, is first cupped by means of dies e, carried by feet f, fixed in movable die head h h, the die head is swung around plates g, fixed by bolts i, in the movable die head parts h h. The die head h h, is composed of two parts held apart by springs w, and guided on bolts u, Fig. 1. The construction of this movable and adjustable die head is more fully described in a co-pending application Serial No. 694,243.

The die head h h, is moved in the curved path Y, by means of the following mechanism. On a cam or disk 19, mounted on the operating shaft s, there is provided a roller 18, which fits into a slot 17, on a lever 15, pivoted at 16. To the short end of the lever 15, there is pivoted at 14, a rod 12. About midway in the length of the rod 12, there is mounted a roller 11, which is guided in a curved slot 10, on a fixed bracket 9. The upper end of the lever 12, is expanded to form a bearing for the swivel 13, for the die head h h. By means of a pin 7, carried by the die head h h, the die head is swung around from the position shown in Fig. 1, to that shown in Fig. 6. This is effected by the pin 7, traveling in the curved groove 8, formed on the upper part of the bracket 9.

The die head h h, passes over two end columns 2, arranged at each side of the machine. These end columns are supported in an inclined position in a fixed sleeve 2, and carry at their lower ends (see Figs. 1^a and 3) arms 3, on which are mounted rollers 4. The roller 4, engages with the face cam 5, to rotate the standards 2, at required times. The rotation of the standards 2, causes the die head parts h h, to come together or expand for the purpose which is more fully explained hereafter. Below the folders c, c 110 Fig. 6, there is mounted a hot presser plate d, this presser plate rests on springs n, and has

a pin h , projecting downwardly to rest on an arm pivoted at p , and carrying a roller l . The roller l , rests on a cam m .

As the shaft s , in Fig. 6, rotates from the point where the position marked I is under the roller l , to the point where the position marked II comes under the roller l , the blank A , is laid on the folding table, the die head is then moving from the position shown in Fig. 1, along the path shown by the dotted line Y on to the guides or columns z . The dies e , are then in the expanded position shown in Figs. 1 and 6. The folders c , are then drawn apart far enough to freely admit the expanded dies e . The dies e , press the blank A on to the hot presser plate d , and thereby pass below the folders c . Immediately the dies e , pass below the folders c , these folders are moved into the positions shown in Fig. 6, in a definite sequence which may be varied as required. From this position until the roller l , starts to rise at the point II, the die heads h, h , are brought together by the rotation of the columns z , and the die heads also start to move upwardly from the table. In order to prevent the movement of the dies e , from scraping or disturbing the blank A , a pin 20 (see Figs. 1 and 3) carried by the die head comes to bear on a spring 21^a contained in a recess 21. This happens when the die head is moving into its lowermost position so that the weight of the die head does not fall on the blank, but is taken up by the spring 21^a. When the point II passes under the roller l , the hot presser table d , is moved upwardly to press the blank. From the points II to III, the blank is pressed and at the point III, the presser plate d , recedes a short distance for the blank whereupon the folders c , are withdrawn. At the point IV, the presser plate d , gets a rapid drop whereby the folded blank falls from the table.

Having described the general operation of the machine, I shall now proceed to deal with the novel features according to this invention. These novel features refer to the timing mechanism of the side folders c , c , and the end folders 22.

Referring to Fig. 5^a, it will be seen that the blank A , shown as a collar blank, has to be folded along the four edges, A' , A^2 , A^3 , A^4 . If various kinds of lock corners are desired, the edges have to be folded in a different sequence, for instance, the side A' may be folded first, whereupon the ends A^3 , A^4 , may be folded and then the side A^2 , may be folded. The operation might be reversed that is to say, the side A^2 , might be folded first, and then the ends A^3 and A^4 , and lastly the side A' . A third alternative would be to fold the sides A' and A^2 simultaneously and first, and the ends A^3 and A^4 , last; or a fourth alternative is possible by

folding the ends A^3 and A^4 first and the sides A' and A^2 , simultaneously and last. According to the present invention, means are provided for securing any one of these alternative methods merely by operating a single setting member and this in spite of the fact that the side folders c , and the end folders 22, move in transverse paths.

The sets of operating cams 54, 54' and 56, 56' for the side folders are in pairs and are all mounted on a common shaft s . The pair of cams 54, 54' are the early and late cams respectively for the lower folder on the left hand side in Fig. 6, that is to the front of the operating shaft s , while the cams 56, 56' are the early and late cams for the upper folder on the right hand side in Fig. 6, that is to the rear of the operating shaft s . The rollers q , are slidably mounted on their spindles 56^a, which are on opposite sides of the shaft s , so as to move the folders c , toward and away from one another. Each slide roller is thus located to co-act with either cam of one pair or set. As seen in Figs. 3 and 4, the rollers q are grooved, so as to leave two projecting parts between which a shifting rod may engage. The roller q , for the left hand side folder in Fig. 6, is formed of two roller parts 53, between which engages an operating bar 51, which is adapted to slide the roller q along its spindle 56^a, so as to bring one or other of the roller parts 53 into engagement with the cam 54 or 54'. The roller q for the right hand side folder in Fig. 6 is composed of two rollers 55, and in a similar manner is caused by the operating bar 52 to slide along its spindle 56^a, to bring one or the other of the roller parts 55 into engagement with the cam 56 or 56'. The arms r , carrying the spindles 56^a are forked and the free space between the arms is sufficient to allow of the necessary sliding movement.

The bars 51, and 52 which engage between the roller parts 53, 53, and 55, 55, are carried by connecting links or tie rods 49 and 50. These tie rods or connecting links 49, 50, are arranged at each side of the machine and are movable by means of pins 47 and 48, carried on disks 43 and 44. The disks 43 and 44, are supported on transverse shafts 41, at each end of the machine. The transverse shaft 41, which might be called a timing shaft, at the right hand end in Fig. 4, is prolonged to the front of the machine as seen more clearly in Figs. 1 and 2. This timing shaft is operable by means of a hand lever 41^a, having a nose piece 41^b, adapted to take into recesses on a wheel 41^c, fixed on the shaft 41. A handle 41^a, is loosely rotatable and by inserting the nose piece 41^b, in one or other of the openings in the disk 41^c, and bringing the handle 41^a, around to a fixed stop 41^d, the required adjustment to effect one or other of the sequences described

above with references to the Fig. 5^a, is effected. The handle 41^a, may take up four successive positions corresponding to the four positions of the timing gear shown diagrammatically in Fig. 5. These four positions are shown consecutively in Fig. 5, in the first and third, the top roller *q*, (having the roller parts 55) has just been shifted while in the alternate positions (that is 10 second and fourth) the bottom roller *q* (carrying the roller parts 53) has just been shifted. Thus in shifting from the first position shown at the left hand side of Fig. 5, to the second position, the roller *q*, which 15 is formed of the parts 53, in Fig. 4, is shifted from engagement with the cam 54, into engagement with the cam 54' while the roller parts 55 remain as they were. In moving from the second to the third position, the roller *q*, formed of the parts 55, moves from engagement with the cam 56, 20 into engagement with the cam 56' while the roller parts 53 remain as they were and so on, each of the rollers being moved at an alternate position of the shifting mechanism.

The disks 43 and 44 as can be seen in Fig. 2, have pins 45 and 46 fixed to their inner faces. The cross shaft 41, is supported between the disks 43 and 44, and on this cross shaft there is loosely mounted a member 38. This member comprises two sleeve portions 42, joined by a yoke portion to which the leading line in Fig. 2, from the reference numeral 38 passes. The support for the cross shaft 41 is located between the sleeve parts 42 of the member 38. On each of the sleeve portions 42, there are provided sloping cam surfaces 45^a and 46^a, against 35 which the pins 45 and 46 bear at their free ends. The member 38 is free to slide on the cross shaft 41 between the disks 43 and 44. One of the sleeve parts 42 has cast on it an arm 39 which is bent at right angles and at its free end carries a roller 40 adapted to bear on a cam 19 (Fig. 2). The left hand sleeve 42 in Fig. 2, has cast on it an arm 37 which is bent as shown, so that at its free upper end it co-acts with a head 50 36 on a pin or bar 35. The pin or bar 35 is fixed to a block 31. The block 31 may be clamped at any desired part of the operating bar 30 for the end folder, so as to enable the device to be used with different 55 sizes of collars.

When the arm 39 is raised by the cam, the arm 37, is caused to press against the head 36, and to thereby operate the end folder 22. To accelerate or retard the end folding 60 operation, the roller 40, is moved axially in Fig. 2. This is effected by the pin 46, passing over the incline 46^a, while the pin 45, comes opposite the sloping incline 45^a. It will thus be seen that the axial position 65 of the roller 40, is dependent upon the an-

gular adjustment of the disks 43 and 44, which are in turn set by the handle 41^a. The disks 43 and 44 however, on their rotation also move the connecting links 49 and 50 and thereby also the rollers 53 and 55. 70 In this way the timing of the side and end folders is effected from a common member in an interdependent manner.

Referring now to Fig. 5, which illustrates diagrammatically the operation of the adjusting mechanism for the side folders. In this figure the disks 43 and 44, have been turned around into the plane containing the two rods 49 and 50. In the position shown in Fig. 5, at the extreme left hand, it will be seen that the pins 46 and 47, are both on the right hand side of the center line joining the two disks. In this way the operating rollers *q*, engage with the early cams 54 and 56. With this adjustment the 80 sides A' and A², would be folded simultaneously and first and the ends A³ and A⁴, would be folded last. On rotating the disks from the position shown in the left hand to the next right hand position shown 90 in Fig. 5, it will be seen that the pin 48, still remains on the right hand side of the center line while the pin 47 has crossed the center line. In this way the bottom roller *q*, will co-operate with the late cam 54' while 95 the top roller *q*, will still co-operate with its early cam 56. In this position the side A' would be folded first, the two ends A³ and A⁴, and the side A² would be folded last. In the third position shown in Fig. 5, the pins 48 and 47, are both on the left hand of the center line and in moving to this position the cam roller 40, will have been retarded on the cam 19, so that the 100 result will be, sides A' and A² will be folded simultaneously and last and ends A³ and A⁴, will be folded first. In the 4th position shown on the extreme right in Fig. 5, the pin 46, remains on the same side of the center line while 47, crosses. The side A², is 105 folded first, the ends and the side A' are then folded. It will be seen that in these movements into successive positions the adjustment of any given roller only takes place at the alternate positions.

The end folder 22, has to be arranged adjustable for various reasons and purposes. First of all the various shapes of collars require different movements and the various lengths or sizes require suitable adjustment 110 of the folders. To these ends the folders 22, are supported in carriers 24, slidably in a bracket 23, which may be clamped by a clamp 23^a to the bed at the desired point.

The brackets 23, are fixed at each side of 125 the machine frame and guide the end folders 22, and their carriers 24. The carrier 24, is caused to make various motions according to the pattern of the collar. The mechanism for carrying out one example of 130

inclined motion is shown. Projecting up from the bracket 23, there are rigid pins 280, shown as three in number.

In Fig. 7, four pins will be seen. One lettered 28 is the operating pin, rotatably mounted in the carrier 24 and made in one piece with a link 290 which is pivoted at 29 to the operating rod 30. The other three pins are fixed to the bracket 23 and are referred to as the pins 280 although for the purpose of avoiding confusion of the drawing only one pin is shown as bearing its reference numeral.

For each size or style of collar there is a special folder carrier 24, and this folder carrier has openings in which the pins 280 have free play. These openings 28^a, are variously shaped as can be seen by the dotted lines in Fig. 7. On the bottom of the carrier 24, there are inclined slots 25, which fit over pivoted guide blocks 26, rotatable about pins 27, fixed in the bracket 23. In the various carriers the slots 25, are at different inclinations and differently spaced so that the end folders 22, are moved up at different angles. The pivoted guide blocks 26, adjust themselves to the angle of the slots 25, so that the one guiding mechanism is adaptable to all the various angles of end folders. To hold carrier 24, in place, a cover plate 230 is slipped over the pins 280, which are notched at their upper ends so as to overlap the plate 230 as shown at 281. To keep the plate 230 pressed into the notches as at 281, a spring latch 300, is provided which presses against a pin 301 on the plate and also on a lever 302. The lever 302 is pivoted on the plate and presses with its free end against the operating pin 28. The operating pin 28, is movable in an enlarged opening 282, in the top plate and is adapted to press against the folder carrier 24. The pin 28, fits in a hole in the carrier plate 24, and moves this carrier plate and of course the end folder 22, when the lever 37, strikes the head 36.

It will be understood that the folders 22, must be moved toward one another or away from one another to suit the size of collar. In order that this adjustment may be easily effected the head 36, (Fig. 7) is carried by a slidible pin 35, formed in one piece with a clamping head 31, surrounding the rod 30. A set screw or the like 32, is used for clamping the head 31 to the rod 30. A spring 33, presses on the clamping head 31 and finds an abutment in a fixed recessed part 34. The spring 33, effects the return movement of the rod 30, and the parts moving therewith to wit pin 28 folder carrier 24 and folder 22.

When it is desired to adjust the end folders to suit the size of collar, the clamp 23^a is slackened as also the clamp 32. The bracket 23, is then moved to the required

position carrying with it the rod 30, which slides in the clamping head 31. On tightening up clamps 23^a and 32, the apparatus is all set and ready for working.

I claim:

1. In a folding machine for collars, cuffs and like blanks, side and end folders, means for operating said folders in variable sequence, comprising operating cams, a plurality of adjustable members co-acting with said cams to operate said folders, and a common member movable into set positions for moving selected adjustable members in definite sequence.

2. In a folding machine for collars, cuffs and like blanks, side and end folders, means for operating said folders in variable sequence, comprising sets of operating cams for said folders, adjustable members slidably mounted to co-act variously with said cams and operate said folders, and a common rotatable shaft and co-operating mechanism for sliding selected adjustable members in definite sequence.

3. In a folding machine in combination, side folders movable toward and away from one another, end folders movable substantially transversely to said side folders and toward and away from one another, means for operating said folders in various sequence comprising an operating shaft, a plurality of operating cams mounted on said shaft, rollers slidably mounted and located to the front and rear of said operating shaft and at the ends to move said folders, a rotatable shaft transverse to said operating shaft and means co-operating with all said rollers and operable from said transverse shaft to slide selected rollers in definite sequence.

4. In a folding machine for collars, cuffs and like blanks, side folders, and means for operating same in various sequence comprising two pairs of early and late operating cams for said folders, two rollers each slidably mounted opposite a different pair of operating cams and means for sliding said rollers to co-operate with a selected cam of each pair.

5. In a folding machine for collars, cuffs and like blanks, side folders, and means for operating same in various sequence comprising a driving shaft, two pairs of early and late operating cams on said shafts, two rollers slidably mounted each opposite a different pair of operating cams and on opposite sides of the shaft, a common adjusting member for said rollers and movable into successive positions to slide said rollers alternately from one cam to the other, substantially as described.

6. In a folding machine for collars, cuffs, and like blanks, side folders and means for operating same in various sequence comprising two pairs of early and late operating

cams for said folders, two rollers each slidably mounted opposite a different pair of operating cams and means for sliding said rollers to coöperate with a selected cam of each pair, comprising a rotatable member arranged to assume set positions, shifting mechanism operated by said rotatable member at alternate set positions substantially as described.

10 7. In a folding machine in combination with movable folders, means for operating said folders in variable sequence comprising a driving shaft, two pairs of early and late cams mounted on said shaft, two adjustable rollers arranged on opposite sides of said shaft to coöperate each with a different pair of cams, a movable member arranged to take up four set positions, and mechanism operated by said movable member and co-acting 15 with said adjusting rollers to move the same alternately as the movable member is shifted to successive set positions.

8. In a folding machine in combination with side folders, a driving shaft, two pairs 25 of early and late operating cams therefor, and mounted on said shaft, operating levers, rollers slidably mounted on said operating levers and on opposite sides of said shaft to engage each with a different pair of operating 30 cams, transverse shafts movable into successive set positions, disks mounted on said transverse shafts, tie rods on each side of said operating shaft and connecting disks on different transverse shafts, bars fixed to 35 said tie rods and engaging said rollers to slide the same alternately on the motion of said transverse shafts into successive positions.

9. In combination with side folders and 40 mechanism for timing their operation in various sequence, said mechanism embracing a rotatable shaft, an end folder, an operating cam therefor, an operating lever therefor, a roller on said lever and engaging said 45 cam, and means on said rotatable shaft for the timing mechanism for sliding said roller on the cam to advance or retard the operation of said end folder.

10. In combination with side folders and mechanism for timing their operation in 50 various sequence, said mechanism embracing a rotatable timing shaft, an end folder, an operating cam therefor, an operating arm for said end folder, and loosely pivoted on said rotatable shaft for the timing mechanism, cam faces on said arm, members rotatable with said timing shaft and engaging said cam faces to slide said arm, a cam roller carried by said arm and in its sliding movement slideable over the operating cam 55 for the end folder.

11. In a folding machine, a movable end folder, a bracket therefor, a plurality of guide bars loosely pivoted on said bracket, a plurality of rigid pins carried by said 60 bracket, a slotted folder carrier, the slots of which engage the said guide bars and said carrier also having openings passing 65 for the end folder.

12. In a folding machine, a movable end folder, a bracket therefor, a plurality of guide bars loosely pivoted on said bracket, a plurality of rigid pins carried by said 70 bracket, a slotted folder carrier, the slots of which engage said guide bars and said carrier also having openings passing loosely 75 over said pins, a cover plate engaging over said rigid pins, and on top of said carrier, a spring holding said cover plate in position, 80 and means for moving said carrier.

13. In a folding machine, an end folder, a bracket supporting said folder, a cam for operating said folder, a lever coöperating with said cam and oscillated thereby, a slideable bar coöperating with said lever, a rod 85 slideable with the folder and mounted in said bracket, and means for clamping said rod to said slideable bar as required.

In testimony whereof I have signed my 90 name to this specification in the presence of two subscribing witnesses.

EDGAR BEVERLEY FENBY.
